Primary Examiner — Derrick Edward Holland(74) *Attorney, Agent, or Firm* — Fay Sharpe LLP(57) **CLAIM**

The ornamental design for a sidewall for an I/O module, as shown and described.

DESCRIPTION

FIG. 1 is a front isometric view of a sidewall for an I/O module showing the new design;

FIG. 2 is a rear isometric view of a sidewall for an I/O module showing the new design;

FIG. 3 is a right side view of a sidewall for an I/O module showing the new design;

FIG. 4 is a rear view of a sidewall for an I/O module showing the new design;

FIG. 5 is a left side view of a sidewall for an I/O module showing the new design;

FIG. 6 is a front view of a sidewall for an I/O module showing the new design;

FIG. 7 is a top view of a sidewall for an I/O module showing the new design; and,

FIG. 8 is a bottom view of a sidewall for an I/O module showing the new design.

Broken lines in the drawings are used to depict environment and do not form any part of the claimed design. Where broken lines abut a claimed surface it is understood that those broken lines represent an unclaimed boundary between claimed and unclaimed surfaces. None of the broken lines form any part of the claimed design.
